(57) **CLAIM**

The ornamental design for an automatic ball setting device, as shown and described.

DESCRIPTION

The product is design to set a golf ball in a specified place, either on a tee or on a hitting surface. A golf club is used to actuate the arm which will allow a single ball to roll down the arm to the specified place. After that ball is hit the process may be repeated until using the balls stored in the device.

FIG. 1 is a side and top perspective view of an automatic ball setting device showing our new design;

FIG. 2 is a side and top perspective view with the movable arm in the down position;

FIG. 3 is a front view thereof;

FIG. 4 is a side view thereof;

FIG. 5 is a back view thereof;

FIG. 6 is a top view thereof; and,

FIG. 7 is a top view with the movable arm in the down position.

The broken lines in FIG. 5 are included for the purpose of illustrating portions of the article that form no part of the claimed design.
